UNITED STATES PATENT OFFICE.

LEOPOLD KOFOL, OF DETROIT, MICHIGAN.

MATCH-SAFE.

1,234,911.

Specification of Letters Patent. Patented July 31, 1917.

Application filed February 2, 1917. Serial No. 146,060.

To all whom it may concern:

Be it known that I, LEOPOLD KOFOL, a subject of the Emperor of Austria, residing at Detroit, in the county of Wayne and State 5 of Michigan, have invented certain new and useful Improvements in Match-Safes, of which the following is a specification, reference being had therein to the accompanying drawings.

10 This invention relates to a match safe or container, and my invention aims to provide a novel match safe wherein simple and effective means are employed, in a manner as hereinafter set forth, for positioning a 15 match so that it may be withdrawn from the match safe and in so doing the head of the match ignited.

15 My invention further aims to provide a match safe having a delivery mechanism that is actuated each time a match is removed, to place another match in position to be withdrawn, and by causing each match to be ignited as it is withdrawn, I aim to prevent matches being removed from the 25 safe except for immediate use, thus eliminating the nefarious practice of unscrupulous persons who appropriate as many matches as possible when the same are gratis.

20 My invention will be hereinafter specifically described and then claimed, and reference will now be had to the drawings, wherein—

Figure 1 is a front elevation of a match safe;

35 Fig. 2 a side elevation of the same, partly broken away;

Fig. 3 is a rear elevation of the match safe, partly broken away;

Fig. 4 is a vertical sectional view of the 40 same;

Fig. 5 is a plan of the bottom plate forming part of the match safe, and

Fig. 6 is a perspective view of a portion of a match chute, or delivering spout.

45 In the drawings, 1 denotes a wall plate having the upper end thereof provided with an opening 2 so that said plate may be suspended from a wall nail or other support. Suitably connected to the side edges of the

50 wall plate 1 is a casing having a front wall 3 and side walls 4, with the front wall 3 of less depth than the side walls 4 and all of said walls of less length than the wall plate 1, thus forming a rectangular structure or

55 container that has the upper edge thereof open to receive matches 5 and of such cross

sectional area that the hand of a person cannot be inserted in the box of the container to obtain matches in the lower part thereof.

Suitably connected to the lower edges of 60 the side walls 4 is a bottom plate 6 provided with an inclined chute or spout 7 having a central bifurcation or slot 8 that permits of matches on the chute being easily gripped. The chute is disposed at an angle relative 65 to the front wall 3 and is in spaced relation to the lower end of said wall, so that the matches 5 within the container can be fed on to the chute.

70 Connecting the side walls 4 is an inclined partition 9 and it is on this partition that the matches 5 are placed to descend by gravity to the lower edges of the partition of the front wall 3. The lower edge of the partition 9 is in spaced relation to the bottom plate 6, and slideable on said bottom plate is a feed plate 10, adapted to be reciprocated thereon to release matches held within the container by the front edge of said feed plate. The feed plate is slotted, 75 as at 11, and held in position by guide pins 12 connected by guide plates 13. The feed plate 10 is slotted or cut away, as at 14, with the slot angularly disposed relative to the front edge of the feed plate. In slotting 80 said feed plate, the material operated upon to form the slot is struck up to provide opposed flanges 15 and operable between these flanges and in the slot 14 is an anti-friction roller 16 carried by the lower end of an arm 85 17 fulcrumed or pivotally held on a stud 18 carried by the bottom side of the inclined partition 9. Pivotally connected to the end of the arm 17, as at 19, are links 20 and these links extend through slots 21 in the lower 90 ends of the side walls 4. A spring 22 connects the lower end of the arm 17 to one of the side walls 4 so as to hold the feed plate 10 normally retracted, thus allowing one of the matches 5 to lodge between the lower 95 edge of the front wall 3 and the front edge of the bottom plate 6, in position to be forced on to the chute 7 when the feed plate 10 is actuated through the medium of the links 20.

100 Fulcrumed or pivotally mounted upon the chute 7, at the upper side edges thereof, as at 23, are converging gripping members 24, said members having the upper ends thereof reduced and pivotally connected, as at 25, to 105 the outer ends of the links 20. The gripping members 24 have the outer edges there-

of rolled or inturned, as at 26, and it is these outer edges of the members that hold said members in spaced relation to the chute 7, while the spring 22 retains the members 24 in a closed position, presenting a somewhat V-shaped or tapering trough or spout into which matches may be sent. The rolled or inturned edges 26 are serrated or roughened, as at 27, so that when withdrawing a match 10 from the chute and from between the gripping members 24, the head of the match will be ignited by striking against the serrated edge of one of the gripping members 24.

The lower faces of the gripping members 24 are provided with resilient members or flat springs 28 adapted to hold matches on the chute 7, particularly while the gripping members 24 are separated, which occurs when the upper ends of said 20 members are pressed toward the side walls 4 of the match container. As this is accomplished the feed plate 10 places a match on the chute 7 and under the spring 28. When the gripping members 24 assume normal position by having the upper ends thereof released, said gripping members are then in position to cause the head of a match being ignited as it is pulled from between said gripping members. The act of withdrawing 30 a match causes the gripping members to be separated, and in this manner another match is automatically delivered to the chute 7 to be held in position for withdrawal.

It is thought that the operation and utility 35 of the match safe will be apparent without further description, and while in the drawing there is illustrated a preferred embodiment of my invention, it is to be understood that the structural elements are susceptible 40 to such variations and modifications as fall within the scope of the appended claims.

What I claim is:—

1. A match safe comprising a container having a bottom plate provided with a 45 chute, an inclined partition in said container, a feed plate on the bottom plate of said container adapted to deliver matches on to the chute of said bottom plate, resilient members on the chute of said bottom 50 plate adapted to temporarily hold matches

on said chute, and gripping members fulcrumed on the chute of said bottom plate and articulated with said feed plate so that withdrawal of a match from said chute causes said gripping members to be actuated 55 and imparts movement to said feed plate.

2. A match safe comprising a container, a chute carried thereby and adapted to receive matches from said container, resilient members on said chute adapted to temporarily hold matches, gripping members fulcrumed on said chute and adapted to cause a match to be ignited when withdrawn from said chute, and a feeding mechanism carried by said container and actuated by said gripping members adapted to feed matches on to said chute.

3. A match safe comprising a container, an inclined partition in said container, a bottom plate carried by said container and provided with a slotted chute, gripping members fulcrumed on said chute and adapted to be actuated by the withdrawal of the match from said chute and at the same time cause the match to be ignited, a feed plate 75 on the bottom plate of said container adapted to feed matches to said chute, and means carried by said inclined partition and actuated by said gripping members adapted for moving said feed plate.

4. A match safe comprising a container, an inclined partition therein, a bottom plate carried by said container and providing a chute, resilient members on the chute of said bottom plate adapted to temporarily hold a 85 match thereon, fulcrumed gripping members on said chute adapted to cause a match to be ignited when withdrawn from between said members, and a feeding mechanism actuated by said gripping members to place matches 90 on the chute of said bottom plate, and including a feed plate, a fulcrumed arm, and links connecting said arm to said gripping members.

In testimony whereof I affix my signature 95 in the presence of two witnesses.

LEOPOLD KOFOL.
